UNITED STATES PATENT OFFICE.

ROY C. GREENFIELD, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

ROD MILL.

Application filed June 19, 1922. Serial No. 569,379.

This invention relates in general to improvements in comminuting apparatus, and relates more specifically to improvements in the construction and operation of rotary drum mills of the type wherein material is reduced by a plurality of elongated rodlike comminuting bodies which are free to roll and tumble about within a revolving comminuting chamber.

10 An object of the invention is to provide a rod mill which is simple in construction and efficient in operation. Another object of the invention is to provide means for effecting convenient access to the interior of a trunnion supported rod mill, without providing manholes in the body of the mill.

It has been common commercial practice to reduce materials having certain characteristics, in rotating mills comprising a drum 20 loaded with freely tumbling comminuting rods. The early commercial mills of this type were supported by means of trunnions, through one of which the material was fed into the drum and through the other of 25 which the comminuted material was discharged. In these early mills, the discharge trunnion opening was ordinarily formed of sufficient size to permit insertion of rods to the interior of the mill, but the body of the 30 mill was provided with manholes or openings through which the mill liners could be inserted. Such manholes were extremely objectionable especially in mills of this type, as it was found impossible to provide sufficiently tight joints between the manhole 35 covers and the mill, to prevent leakage of material. The use of manholes and covers therefor was also objectionable because of the inconvenience caused by the removal and 40 replacement of the manhole covers, and because such construction was expensive and weakened the shell.

It was later proposed to modify the construction of rod mills by providing an open 45 discharge end and by supporting the mill upon roller bearings coacting with a tire at the periphery of the drum adjacent to the discharge end of the mill. While such open-ended mill construction eliminated necessity 50 of providing manholes in the body of the mill, it has proven objectionable for a number of reasons. One of the objections to the open-ended mill construction is the fact that it requires considerably more power to oper-

ate a mill having roller bearings coacting with the periphery of the shell, than it requires to operate a trunnion supported mill wherein the bearing surfaces are relatively near to the mill axis. Another objection to the open-ended mill structure is the fact that with such a structure it is difficult to maintain a proper liquid and material discharge level, it having been found that the capacity of this type of mill is increased by providing a relatively small central discharge opening and thereby raising the liquid level. The open-ended type of mill is also objectionable since it is difficult with such a mill to adjust the bearings and the height of the overflow, and because of the greater cost of 70 construction of open-ended mills as compared with trunnion supported mills.

The present invention contemplates the provision of a trunnion supported rod mill in which the discharge trunnion and the 75 discharge head liners are provided with aligned openings which are of sufficient size to permit easy entry of a man, insertion of the liner sections and insertion of the comminuting rods, without necessitating disconnection of the end heads and without providing manhole openings in the body of the drum. With such a mill the power necessary for operation is reduced to a minimum and the overflow level may be readily varied 80 to produce the desired capacity and degree of fineness of the discharged material, by merely providing discharge trunnion liners of varying shapes and thickness. As it has been found that an opening in order to serve 85 as a manhole should be over 14" in diameter, the available opening through the trunnion and end head liners, should be at least this amount. In order to reduce the diameter of the discharge trunnion bearing to a 90 minimum, it is preferable that the discharge opening be of a size at most one-third of the diameter of the comminuting chamber. These limiting dimensions are features of 95 the present invention.

100 A clear conception of several embodiments of the invention and of the operation of mills constructed in accordance therewith may be had by referring to the drawing accompanying and forming a part of this 105 specification in which like reference characters designate the same or similar parts in the various views.

Fig. 1 is an elongated vertical section through an improved rod mill of the trunnion-supported type.

Fig. 2 is a transverse vertical section through the rod mill shown in Fig. 1, looking toward the inlet end of the mill.

Fig. 3 is an end view of the rod mill looking toward the discharge end of the mill.

Fig. 4 is a fragmentary central vertical 10 longitudinal section through a modified form of discharge end head and trunnion liners.

The rod mill illustrated in the drawing 15 comprises generally a cylindrical drum or shell 2 having feed and discharge end heads 3, 4 provided with trunnions 18, 19 respectively, which are supported in bearings 6, 7 respectively. The trunnion bearings 6, 7, are also preferably provided with adjusting 20 means 21 for insuring proper alignment. The feed end head 3 is provided with a gear 5 for imparting rotary motion to the mill. The interior of the shell 2 is provided with a sectional lining 8, the sections 25 of which are preferably formed of several lengths but of approximately the same width and thickness. The feed end-head 3 is provided with a sectional lining 9 having a central opening cooperating with a tapered inlet opening formed in the feed trunnion liner 11. The discharge end-head 4 is provided with a sectional lining 10 which is preferably composed of sections identical with the sections of the feed end-head liner 9, thereby making the end-head liners interchangeable. The discharge end-head liner 10 has a central discharge opening of size 10 approximately equal to the discharge opening of the discharge trunnion liner 12. In 40 Fig. 1, the diameter of the mill discharge and manhole opening ϖ is preferably over 14" and is at most one-third of the diameter of the interior of the shell 2 in order to reduce the trunnion diameter to a minimum and to establish a suitable overflow level in 45 the mill. The interior of the mill is preferably loaded substantially as indicated with elongated freely tumbling comminuting rods 15 extending substantially throughout the 50 entire length of the mill. The mill is also provided with suitable feed mechanism for admitting the raw material 16 to the mill through the feed trunnion liner 11, and the finished product 17 is discharged through 55 the mill discharge end opening ϖ as illustrated in Fig. 1.

The shell 2 may also be provided with a tire 13 adapted to coat with rollers 14 which are adjustable toward and away from the tire 13 by means of adjusting screws 20. These rollers 14 are withdrawn from the tire 13 during normal operation of the mill and are provided merely to serve as a temporary support for the discharge end of the mill 60 permitting adjustable rotation thereof when

it is found desirable to remove the discharge end-head 4 and the associated elements. Such removal of the end-head may be desirable when it is desired to remove the entire charge or the entire lining from 70 within the mill. The temporary roller support may be omitted as it constitutes merely a convenient assembling rig.

In the modified form of discharge mechanism illustrated in Fig. 4, the mill discharge end manhole opening ϖ is defined by the aligned openings of the trunnion 19 and of the end-head liner 23. In this structure the discharge trunnion liner 22 may be provided with a constricted portion 24 determining the actual discharge orifice and level. As the trunnion liner 22 may be conveniently withdrawn, a mill provided with such discharge structure possesses practically all of the advantages of the mill illustrated in 85 Figs. 1 to 3 inclusive. The feed end-head liners of such a mill would preferably be identical with the discharge end-head liners 23 illustrated in Fig. 4, in order to provide for interchangeability of the head liners. 90

During normal operation of the mill the interior of the mill is provided with a charge or rods and of material substantially as illustrated, the rods 15 preferably lying in lateral contact with each other and being 95 of various diameters. As the raw material 16 is fed into the mill and the drum or shell 2 is rotated in the direction indicated, the rods 15 cascade over the charge and impinge against the material in the bottom of 100 the comminuting chamber. The material is preferably removed from the mill by the admission of water which carries the fine material 17 through the opening in the discharge trunnion liner, as indicated. By confining 105 considerable water in the mill with the aid of the end-heads 3, 4, the finished product 17 is freed from the pulp by the washing action of the liquid and quickly rises to the surface of the water and is discharged with 110 the overflow.

It will be obvious that by providing a mill end manhole opening ϖ which is at least 14" in diameter and at most one-third of the diameter of the comminuting chamber, the 115 opening ϖ will serve as a manhole and a suitable overflow level is maintainable within the mill. By providing identical trunnion supports for opposite ends of the mill, the power consumption may be reduced to 120 a minimum and the feed and discharge end-head liner structures may be made interchangeable. The trunnion supporting bearings 6, 7, may also be made of similar structure thus reducing to a minimum the 125 cost of construction and of operation of mills of this type.

It should be understood that it is not desired to limit the invention to the exact details of construction and of operation here- 130

in shown and described, for various modifications within the scope of the claims may occur to persons skilled in the art.

It is claimed and desired to secure by Letters Patent:—

1. In combination, a rotary casing and feed and discharge end heads coacting therewith to form a comminuting chamber, said casing being free from manhole openings, a plurality of freely tumbling rods within and extending substantially the entire length of said chamber, and a supporting trunnion for the mill associated with said discharge end head, said discharge end head having a central manhole opening through said trunnion of sufficient size to permit free transfer of rods therethrough, said opening being of less diameter than one-third of the diameter of said chamber at said head but greater than fourteen inches and the space in line with said opening being unobstructed throughout the length of the mill.
2. In combination, a rotary casing and feed and discharge end heads coacting therewith to form a comminuting chamber, said casing being free from manhole openings, a sectional lining for said chamber, a plurality of freely tumbling rods within and extending substantially the entire length of said chamber, and a supporting trunnion for the mill associated with said discharge end head, said discharge end head having a central manhole opening through said trunnion of sufficient size to permit free transfer of said lining sections and of said rods therethrough, said opening being of diameter less than one-third of the diameter of said chamber but greater than fourteen inches and the space in line with said opening being unobstructed throughout the length of the mill.
3. In combination, a rotary casing forming a comminuting chamber, said casing being free from manhole openings, a plurality of freely tumbling rods within and extending substantially the entire length of said chamber, a head coacting with the discharge end of said casing and having a trunnion support of relatively small diameter secured centrally thereto, and a liner for said discharge end head having a central manhole opening through said trunnion of sufficient size to permit free transfer of said rods therethrough, said opening being of diameter less than one-third of the diameter of said chamber but over fourteen inches and the space in line with said opening being unobstructed throughout the length of the mill.
4. In combination, a rotary casing forming a comminuting chamber, said casing being free from manhole openings, a plurality of freely tumbling rods within and extending substantially the entire length of said chamber, feed and discharge end heads secured to opposite ends of said casing, a supporting trunnion connected centrally with each of said heads, and interchangeable liners associated with said heads, each of said liners having a central manhole opening extending through said trunnion of an adjacent head and of sufficient size to permit free transfer of rods therethrough, and each of said openings being of diameter less than one-third of the diameter of said chamber but over fourteen inches and the space in line with said openings being unobstructed throughout the length of the mill.
5. A trunnion supported lined manhole-free mill having an opening through one of its trunnions of size sufficient for the passage of a man.
6. A trunnion supported lined manhole-free mill having an opening through one of its trunnions of size sufficient for the passage of liner sections.
7. A trunnion supported lined manhole-free mill having an unobstructed opening through its discharge trunnion of size sufficient for the passage of a man.
8. A trunnion supported lined manhole-free mill having an unobstructed opening through its discharge trunnion of size sufficient for the passage of liner sections.

In testimony whereof, the signature of the inventor is affixed hereto.

ROY C. GREENFIELD.
